US0D1093322S

(12) **United States Design Patent** (10) **Patent No.:** **US D1,093,322 S**
Chen (45) **Date of Patent:** **** Sep. 16, 2025**

(54) **WIRE CONNECTOR**

(71) Applicant: **XIAMEN GHGM INDUSTRIAL TRADE CO., LTD**, Xiamen (CN)

(72) Inventor: **Bingshui Chen**, Xiamen (CN)

(73) Assignee: **XIAMEN GHGM INDUSTRIAL TRADE CO., LTD**, Xiamen (CN)

(**) Term: **15 Years**

(21) Appl. No.: **29/932,285**

(22) Filed: **Mar. 13, 2024**

(30) **Foreign Application Priority Data**

Jan. 19, 2024 (CN) 202430039050.5

(57) **CLAIM**

The ornamental design for a wire connector as shown and described.

DESCRIPTION

FIG. 1 is a perspective view of a wire connector showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines in the drawings depict portions of the wire connector that form no part of the claimed design.

1 Claim, 9 Drawing Sheets
